UNITED STATES PATENT OFFICE

143,603

DESIGN FOR AN ELECTRON DISCHARGE TUBE

Norman B. Krim, Newton Highlands, Mass., assignor to Raytheon Manufacturing Company, Newton, Mass., a corporation of Delaware

Application February 22, 1945, Serial No. 118,089

Term of patent 14 years

(Cl. D26—8)

To all whom it may concern:

Be it known that I, Norman B. Krim, a citizen of the United States, residing at 1007 Walnut Street, Newton Highlands, in the county of Middlesex and Commonwealth of Massachusetts, have invented a new, original, and ornamental Design for Electron Discharge Tubes, of which the following is a specification, reference being had to the accompanying drawing, forming part thereof in which

Fig. 1 is a front elevation;
Fig. 2 is a side elevation; and
Fig. 3 is a bottom plan view of an electron discharge tube showing my new design.

I claim:

The ornamental design for an electron discharge tube, substantially as shown.

NORMAN B. KRIM.
